(57) **CLAIM**

The ornamental design for an otoscopic instrument head, as shown and described.

DESCRIPTION

FIG. 1 is a front perspective view of an otoscopic instrument head, illustrating our new Design;

FIG. 2 is a rear perspective view thereof;

FIG. 3 is a top plan view thereof;

FIG. 4 is a left side elevation view thereof, the right side elevation view being a mirror image thereof;

FIG. 5 is a bottom view thereof;

FIG. 6 is a right side elevation view, further illustrating, in phantom, an attached otoscopic tip and diagnostic instrument handle for use therewith;

FIG. 7 is a front view of the instrument head; and,

FIG. 8 is a rear view thereof.

The broken line showing is for illustrative purposes only and forms no part of the claimed design.
